OPERATING MECHANISM FOR CLOSURES

George H. Kohlsaat, De Smet, S. Dak.

Application June 14, 1937, Serial No. 148,237

1 Claim. (Cl. 119—116)

This invention relates to an operating mechanism for closures and has for an object to provide novel mechanism for opening the doors and releasing live stock from barns in the event of fire and at other times.

A further object is to provide a system of flexible connectors connected to the closures, such as the barn doors and doors to box stalls, and arranged so that they may be operated from the dwelling house to open and close the closures.

A further object is to provide lever mechanism associated with the flexible connectors for rotating tethering rails for the stanchioned animals, to release the halters of the animals simultaneously with the opening of the closures.

A further object is to provide a device of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawings forming part of this specification,

Figure 1 is a horizontal sectional view through a barn equipped with live stock releasing mechanism and closure operating mechanism constructed in accordance with the invention.

Figure 2 is a fragmentary view of the rear wall of the barn showing the arrangement of the closure operating flexible connectors thereon.

Figure 3 is a fragmentary view of the front wall of the barn showing the closure operating flexible connectors and also the lever mechanism for operating the tethering rails.

Figure 4 is a vertical sectional view through the barn taken on the line 4—4 of Figure 1 and showing the tethering rails and a portion of the closure operating mechanism.

Figure 5 is an enlarged detail of a portion of Fig. 4 showing one of the tethering rails in full lines in operative position and in dotted lines in released position.

Figure 6 is a detail plan view of one of the tethering rails and the ring engaged on the pin of the tethering rail.

The invention may be applied either to the inside or the outside or part on the inside and

part on the outside of a barn, and other places where live stock is confined.

Referring now to the drawings in which like characters of reference designate similar parts

in the various views, a barn is shown with stalls 10 arranged on opposite sides of a center aisle 11, and along one side wall of the barn. The stalls have respective mangers 12. An oat bin 13 is located against one end wall of the barn and box stalls 14 are located along one side wall of the barn. These parts are conventional.

In carrying out one feature of the invention I provide a rotatable tethering rail 15 for each row of stalls 10. As shown in Figures 5 and 6 pins 16 project radially from the rail and normally extend upwardly to a position just underneath a shelf 17 best shown in Figure 5, the shelf preventing escape of the tethering rings 18 of the tethers 19 from the pins. When the shaft is rotated axially all of the pins are swung to the dotted line position and release the rings 18 simultaneously to free the animals. The tethering rails 15 are rotatably mounted in any preferred manner on the end walls of the barn and are rotated by lever and flexible connector mechanism hereinafter fully described.

Doors 20 in the end walls of the barn form exits for the stalls 10 and these doors are slidably suspended from tracks 21 by eyes 22. Similar doors 23, see Figure 1, afford access to and exit from the box stalls 14 and these doors also are slidably suspended from tracks 24 by means of eyes 25. All of the doors are simultaneously slidable to open or to closed position by a system of levers and flexible connectors which will now be described.

A pair of levers 26 are swingingly mounted at the lower ends on a wall of the barn, see Figure 3, and to accomplish this the levers are fixed to the projecting ends of the revoluble tethering rails 15 which project through the wall of the barn. A link 27 is pivotally connected at the ends to the upper ends of the levers to couple the levers together for movement as a unit. A pull flexible connector 28 is connected to one of the levers and is trained through a sheave 29 carried by a post 30 and thence is conducted into the dwelling.

A flexible connector 31 is connected to the link 27 and to one of the doors 20 as shown in Figure 3, and a flexible connector 32 connects both doors together. Consequently, when the flexible connector 28 is pulled the levers will be moved in the direction of the arrowheads in Figure 3, and both of the doors will be slid to open

position. At the same time the tethering rails to which the levers 26 are attached will be rotated to release the rings of the tethers and free the animals.

A pull flexible connector 33, see Figure 3, for shutting the doors and resetting the tethering rails after each actuation is conducted from the dwelling to a sheave 34 on the post 30 and is connected to one of the doors 20. When the pull flexible connector 33 is pulled toward the left in Figure 3 both doors 20 are simultaneously closed through the instrumentality of the beforementioned flexible connector 32 which connects the doors, and at the same time through the instrumentality of the flexible connector 31 the link 27 is moved toward the right to initial position for the next operation.

For operating the doors on the opposite end of the barn, shown in Figure 2, a flexible connector 35 is connected to the link 27 and trained through an opening 36 in the wall of the barn as shown in Figure 3, thence is trained through guides 37 inside of the barn, as shown in Figures 1 and 4. The flexible connector 35 is connected to the door of the nearest box stall 14. A flexible connector 38 connects this door with the door of the next adjacent box stall. A flexible connector 39 is connected to the last named door and is trained over sheaves 40 at the opposite end of the barn and thence conducted through an opening 41 in the end wall of the barn, see Figure 2, thence trained through a sheave 42 on the outside of the barn and terminally connected to one of the doors 20. A flexible connector 43 is terminally connected to the chain 39 inside of the barn and is conducted to the outside of the barn through an opening 44, thence is trained through a sheave 45 on the outside of the barn and terminally connected to the other door 20.

When the link 27 is moved endwise by a pull upon the release flexible connector 28 the flexible connector 35 will be pulled and will slide to open position both doors of the box stalls and both doors on the rear wall of the barn, simultaneously with the opening of both doors on the front wall of the barn and live stock releasing movement of the tethering rails.

For resetting the lever and flexible connector mechanism to close the doors and return the tethering rails to operative position, as best shown in Figure 1, the resetting flexible connector 33 is connected to a flexible connector 45 which is trained over sheaves 46 on one of the side walls of the barn and thence is connected to one of the doors 20 on the rear wall of the barn, as best shown in Figure 2. A flexible connector 47 is connected to the chain 45 and is trained over sheaves 48 and thence is terminally connected to the other sliding door as also shown in Figure 2.

When the resetting flexible connector 33 is

pulled toward the right (in Figure 1), the chain 45 will also be pulled toward the right. The doors 20 shown in Figure 2 are moved away from the center of this figure. These doors pull the flexible connector 39 and flexible connector 43, and cause the flexible connector 38 to move toward the left (in Figure 1). This causes the flexible connector 35 to move the link 27 to the right (in Figure 3).

By referring again to Figure 3 it will be seen that a lever 49 is fixed to the projecting end of the tether rail of the centermost row of stalls and is connected by a flexible connector 50 to the link 27. A lug 51 of substantially V-shape in horizontal cross section projects from the side of the link 27. When the link 27 has been moved endwise to door closing position by pull upon the flexible connector 35, the lug 51 and lever 49 will be in the position shown in full lines in Figure 3 and the lever 49 will ride over the lug when the link 27 moves to the left to door opening position in Figure 3 and pulls the flexible connector 50 to move the lever 49. Thus the lug 51 merely acts as a yielding stop.

Since the operation of the device has been described as the description of the parts progressed it is thought that the invention will be fully understood without further explanation.

What is claimed is:

30. Operating mechanism for closures comprising the combination of a barn for housing livestock, rotatable tethering rails arranged on opposite sides of a center aisle and along one wall of the barn, pins projecting radially from the rails and normally extending upwardly, shelves arranged above the rails and coacting with the pins for holding tethering rings of halters, said rails projecting exteriorly of the barn, tracks on the barn adjacent door openings in the barn, doors for said openings slidably mounted on the tracks, a pair of outer upstanding levers fixed respectively to the projecting end of one of the center aisle rails and to the tethering rail along one wall of the barn, an intermediate upstanding lever fixed to the projecting end of the other center aisle rail, a link connecting both outer levers together for movement simultaneously in the same direction to rotate their respective tethering rails and carry the pins downward to release the tethering rings, a flexible connector connected to said link and to said intermediate lever and adapted to move the intermediate lever simultaneously with and oppositely to the outer levers to rotate its respective tethering rail to carry the pin downward to release the tethering rings, flexible connectors connecting the doors to the outer levers for moving the levers as a unit with the doors, a flexible connector connected to one of the doors for manually closing the doors, and a flexible connector connected to one of said outer levers for manually opening the doors.

GEORGE H. KOHLSAAT.
